UNITED STATES PATENT OFFICE.

RAY A. PRESS, OF GRINNELL, KANSAS.

DISK-HARROW SPINDLE AND BOXING.

1,391,853.

Specification of Letters Patent. Patented Sept. 27, 1921.

Application filed March 30, 1921. Serial No. 456,890.

To all whom it may concern:

Be it known that I, RAY A. PRESS, a citizen of the United States, residing at Grinnell, in the county of Gove and State of Kansas, have invented certain new and useful Improvements in Disk-Harrow Spindles and Boxings, of which the following is a specification, reference being had to the accompanying drawings.

10 It is the purpose of the present invention to provide a disk harrow spindle and boxing, the construction of which embodies simplicity, efficiency and practicality, there being ball bearing parts, to insure easy revoluble movements for the disks.

Another purpose is to provide a construction of this character, which may be easily assembled and taken apart, there being coupled connection between the harrow disks 20 adjacent the opposite ends of the boxing, whereby the turning of one disk, will impart movement to the other and vice versa.

While the design and construction at present illustrated and set forth is deemed preferable, it is obvious that as a result of a reduction of the invention to a more practical form for commercial purposes, the invention may be susceptible of changes, and the right to these changes is claimed, provided 30 they are comprehended within the scope of what is claimed.

The invention comprises further features and combination of parts as will be hereinafter set forth, shown in the drawings and 35 claimed.

In the drawings:

Figure 1 is a view in elevation showing a part of the harrow frame, and illustrating the improved disk harrow spindle and boxing as applied.

Fig. 2 is a vertical sectional view through the same showing it constructed in accordance with the invention.

Fig. 3 is a cross sectional view on line 45 3—3 of Fig. 2.

Fig. 4 are detail views of the adjacent ends of the two projecting sleeves of the disks, whereby the disks may rotate together.

Referring to the drawings, 1 designates a 50 shaft, on which the disk harrow spindle and boxing are mounted, and 2 denotes a harrow frame on which a depending arm 3 is carried.

This depending arm 3 is connected to a 55 boxing 4, since the arm engages a depression or cavity 5 of an enlargement 6 of the box-

ing, there being a transverse bolt or pin 7 extending through the enlargement and the lower end of the arm 3 to securely unite the boxing.

The boxing 4 comprises the upper and lower sections 8 and 9, which are substantially semi-circular in cross section and which are chambered out as shown at 10 and 11. These sections have lateral ears 12, 65 which are secured together by means of the bolts 13. The interiors of the sections 8 and 9 have semi-circular flanges or walls 14 and 15. The flange 14 is spaced from the outer end (which has a flange 16) of the 70 sections or boxings, so has to provide a semi-annular space 17, which receives the rings 18 and 19.

A harrow disk 20 is provided, and projecting from and carried by the disk in any 75 suitable manner is a spindle sleeve 21, which rotatably fits the shaft 1, there being a nut 22 and washer 23 for holding the disk 20 on the shaft. This spindle sleeve 21 is threaded as shown at 24, and engages with 80 the threads of the ring 19, holding the ring 19 in position on the spindle sleeve. The spindle sleeve passes through the opening 25 of the ring 18. The rings 18 and 19 have adjacent beveled faces 26 and 27, which 85 are provided with annular race-ways 28 and 29, in which one or more ball bearings 30 are operable, so as to insure easy revoluble movements of the parts. It is obvious that by threading the ring 19 on the spindle 90 sleeve and since the ring 19 engages the cavities or annular spaces 17 of the boxing, the harrow disk 20 is retained in place relatively to the boxing.

A second harrow disk 31 is mounted upon 95 the shaft 1, and its spindle sleeve 32 extends into the boxing. The spindle sleeve 32 has a radial flange 33, which engages between the semi-circular flange 15 and the semi-circular flanges 34 which are carried by the 100 inner ends of the sections of the boxing, thereby not only preventing accessive movement of the harrow disk 31 toward the boxing, but also preventing accessive inward movement. In fact by this construction the 105 disk harrow 31 is retained in position relatively to the boxing and the other dependent parts.

The adjacent ends of the spindle sleeves 21 and 32 have notch and tooth connections 110 35 and 36, so that the disks 20 and 31 will rotate together, during the operation of the

machine. Arranged in the semi-cylindrical cavities 10 and 11 of the two sections of the boxing is a hard wood filler or sleeve 37, which is located between the flanges 14 and 15 of the sections of the boxing, thereby constituting bearings for the sleeves of the spindles of the harrow disks. This wood filler or sleeve when worn may be easily renewed or replaced, by simply separating the two sections of the boxing, which not only permit the filler or sleeve to be replaced, but will also permit the harrow disks to be separated, and removed from the shaft 1.

It is obvious that the shaft 1 may support harrow disks, arranged in pairs as illustrated, and rotatable together, for farming purposes, permitting the harrow disks to rotate together in pairs, throughout the length of the shaft, though it is obvious that one, or any number of harrow disks can be similarly mounted upon the shaft.

The invention having been set forth, what is claimed as being useful is:

In a disk harrow spindle, a boxing, a shaft, a pair of harrow disks mounted upon the shaft and having their adjacent faces

provided with spindle sleeves, slot and lug connections uniting the sleeves, whereby both disks may operate together, an annular ring threaded to one of the sleeves, a second annular ring fitted in the boxing, the two rings having adjacent beveled faces provided with race-ways for the reception of anti-frictional members, the outer end of said boxing having an annular flange co-operating with a ring which is threaded on one of the spindle sleeves, to retain one harrow disk and spindle sleeve on the shaft, the other end of the boxing having a radial flange, and an interior radial flange, a flange 40 on the spindle sleeve of the other harrow disk engaging between the last two mentioned flanges to connect the second harrow disk to the boxing, the interior of the boxing near one of the rings having an annular flange, and a hard wood filler sleeve mounted on the boxing surrounding the two spindle sleeves and interposed between the interior flanges of the bearing boxing.

In testimony whereof I hereunto affix my signature.

RAY A. PRESS.
